United States Patent Office

Des. 174,882
Patented May 31, 1955

174,882

CAP

Sol Lipkin, Minneapolis, Minn.

Application January 14, 1955, Serial No. 33,987

Term of patent 7 years

(Cl. D3—13)

FIG. 1

FIG. 2

To all whom it may concern:

Be it known that I, Sol Lipkin, a citizen of the United States, residing at Minneapolis, in the county of Hennepin and State of Minnesota, have invented a new, original, and ornamental Design for a Cap, of which the following is a specification, reference being had to the accompanying drawing, forming part thereof.

Fig. 1 is a top perspective view of a cap showing my new design;

Fig. 2 is a side elevational view;

Fig. 3 is a front elevational view thereof; and

Fig. 4 is a rear elevational view.

I claim:

The ornamental design for a cap, as shown.
